COMBINED CANE AND CRUTCH

Burmain A. Grimball, Charleston, S. C.

Application October 27, 1949, Serial No. 123,944

1 Claim. (Cl. 135—50)

1

My invention relates to a combined cane and crutch.

An important object of my invention is to provide a combined cane and crutch which may be constructed from aluminum tubing, or the like, whereby the device will be extremely strong, yet light in weight.

A further object of the invention is to provide a crutch which is readily adjustable through a wide range of heights.

A still further object of the invention is to provide a combined cane and crutch which is highly simplified, compact, neat and attractive in appearance, and relatively inexpensive to manufacture.

Other objects and advantages of my invention will be apparent during the course of the following description.

In the accompanying drawings, forming a part of this application, and in which like numerals are employed to designate like parts throughout the same,

Figure 1 is a side elevation of a combined cane and crutch embodying my invention, and illustrating the use of the same as a crutch,

Figure 2 is a side elevation of the device with the parts arranged for use as a cane,

Figure 3 is an enlarged fragmentary central vertical section through the device shown in Figure 2, and,

Figure 4 is a similar section through the lower end of the device as shown in Figure 2.

In the drawings, where for the purpose of illustration is shown a preferred embodiment of my invention, the numeral 10 designates an outer straight cylindrical tubular shank or body portion, open at its top and bottom ends. Near its bottom end, the tubular shank 10 is provided with a single transverse opening 11, receiving a transverse bolt 12, which also extends through any selected one of a plurality of longitudinally spaced transverse openings 13, formed in a short straight tube section or sleeve 14, telescopically mounted within the lower end of the tubular shank 10, Figure 4. The short tube section at the bottom of the shank 10 may be adjusted longitudinally, by engaging the bolt 12 in different openings 13. At its bottom end, the tube section 14 is provided with a removable rubber foot 15, or anti-slip device, as shown.

Near and below its top end, the tubular shank 10 has a transverse relatively short tubular extension or handle 16, rigidly secured thereto, and preferably integral therewith. This handle 16 is cylindrical and open at its outer end, and

2

the bore of the handle leads into the bore of the tubular shank 10. Adjacent to the handle 16, the shank 10 is provided in its side remote from the handle with a single locking aperture 17, in axial alignment with the central longitudinal axis of the handle, which is at right angles to the longitudinal axis of the tubular shank 10. The handle 16 is internally screw threaded at its outer end, as shown at 18, for 10 the reception of a screw threaded plug 19, fixedly mounted therein and having a central axial bore 20 in alignment with the locking aperture 17. A straight transverse locking pin 21, for a purpose to be described is longitudinally slidably 15 mounted within the bore 20 and is adapted to have its inner end project through the aperture 17, Figure 3 when the locking pin is in the inner most or locking position. The locking pin 21 has an outer knob or disc 22 rigidly secured 20 thereto adjacent to the outer end of the handle 16, and adapted to abut the outer end of the handle when the locking pin is in the inner position. The knob or disc 22 has its marginal edge projecting radially beyond the periphery of 25 the tubular handle 16. An expandable coil spring 23 is mounted within the tubular handle 16 and surrounds the pin 21. The outer end of this spring engages the plug 19 and its inner end engages a washer 24, secured to the pin 21 for longitudinal movement therewith. The spring 30 thus serves to bias the pin 21 toward its innermost locking position, and yields when the knob or disc 22 is pulled outwardly so that the pin 21 may be retracted from the tubular shank 10. 35 Mounted within the top end of the tubular shank 10 is an inner cylindrical straight tube or crutch staff 25, which when lowered extends within the tubular shank 10 for the major portion of its length, Figure 2. This crutch staff 25 is provided near and above its bottom end 40 with a plurality of longitudinally spaced transverse adjusting apertures 26, and the uppermost aperture 26 is preferably located near the longitudinal center of the crutch staff 25, so that the staff may be adjusted longitudinally a substantial 45 distance. The crutch staff 25 is freely slideable within the tubular shank 10 and any of the openings 26 are adapted to register with the aperture 17 and receive the locking pin 21, so that the crutch staff may be locked in the selected adjusted position. Near and slightly 50 below its top end, the crutch staff 25 has a single transverse opening 27, also adapted to receive the locking pin 21, for holding the crutch staff in its lowermost position, Figure 2.

When in the lowermost position, the top of the crutch staff 25 projects slightly above the top of the tubular shank 10, Figure 3, and is externally screw threaded as shown at 28, for the reception of a short depending tubular internally screw threaded extension 29 of a slightly longitudinally curved transverse tubular arm piece 30, preferably formed integral with the extension 29. Set screws 31 may be provided for locking the arm piece 30 in position upon the top end of the crutch staff. When the crutch staff is lowered, Figure 2, and the locking pin 21 is in the openings 17 and 27, the bottom of the extension 29 abuts the top end of the tubular shank 10, as shown. The cross piece 30 extends parallel to the handle 16.

In use, the bottom tube section 14 is adjusted to position the handle 16 at the correct and comfortable height for a given person. With the crutch staff 25 lowered, Figure 2, the handle 16 may be grasped and the device will serve the same purposes as any conventional cane. When it is desired to use the device as a crutch, the locking pin 21 is retracted and the crutch staff is extended to the desired length, Figure 1, the pin 21 being reinserted in the selected opening 26 which has been brought into registration with the locking aperture 17.

If desired, when the device is used as a cane, the crutch staff 25 may be removed entirely.

It is to be understood that the form of the invention herewith shown as described is to be taken as a preferred example of the same, and that various changes in shape, size and arrangement of parts may be resorted to, without departing from the spirit of my invention or the scope of the subjoined claim.

Having thus described my invention, I claim:

A combined cane and crutch comprising an elongated tubular shank, a transverse tubular handle secured to the tubular shank near the

top end of the shank and extending beyond one side of the tubular shank, the tubular shank having a transverse locking aperture adjacent to the transverse tubular handle, an elongated crutch staff telescopically mounted within the tubular shank and having a plurality of longitudinally spaced transverse openings for registration with the locking aperture, a cross piece secured to the upper end of the crutch staff, a longitudinally shiftable transverse locking pin mounted within the transverse tubular handle and extending entirely through the tubular handle, the inner end of the locking pin being adapted to enter the locking aperture and a selected one of the transverse openings of the crutch staff for releasably locking the crutch staff in a selected adjusted position, a spring mounted within the tubular handle and connected with the locking pin and urging it longitudinally inwardly, and a knob secured to the outer end of the locking pin beyond the outer end of the tubular handle and having its marginal edge projecting beyond the periphery of the tubular handle so that the locking pin may be retracted by sliding the handle longitudinally along the tubular handle into engagement with the knob to pull the knob outwardly.
